CAR COUPLER

William J. Metzger, East Cleveland, Ohio, assignor to National Malleable and Steel Castings Company, Cleveland, Ohio, a corporation of Ohio

Application September 10, 1947, Serial No. 773,127
In Australia January 29, 1947

13 Claims. (Cl. 213—151)

1

This invention relates to car couplers and more particularly to coupler aligning means thereon.

It is an object of my invention to provide a car coupler having novel interlocking wings at the sides thereof to guide the coupler into mating engagement with a similar coupler.

Another object is to provide means at the sides of a coupler adapted to interengage with similar means on another coupler to guide the couplers into mating engagement and to limit relative vertical movement therebetween.

A further object is to provide means at the sides of a coupler for interengaging with complementary means on a similar coupler to guide the couplers into engagement, said means comprising a convexly shaped projection on one side of the coupler and a concavely shaped socket on the other side of the coupler.

A further object is to provide means at the sides of a coupler adapted to cooperate with complementary means on a similar coupler in such a manner as to have rotating contact therewith during the coupling of two couplers.

A more specific object is to provide in a coupler of the knuckle type gathering means comprising a wing on the knuckle side of the coupler having a rounded end surface and a complementary socket on the guard arm side of the coupler for cooperating with the wing of a mating coupler.

Other objects and advantages of my invention will be apparent from the following description thereof taken in conjunction with the drawings in which:

Fig. 1 is a horizontal sectional view of the coupling portions of two couplers embodying the invention, the couplers being coupled and in pulled position.

Fig. 2 is a horizontal sectional view similar to Fig. 1 but showing the couplers in buffed position.

Fig. 3 is a similar horizontal sectional view showing the couplers angled laterally with respect to each other.

Fig. 4 is a side elevational view of two coupled couplers in pulled position corresponding to that shown in Fig. 1.

Fig. 5 is a plan view illustrating the coupling of two couplers which are angled laterally with respect to each other, one knuckle being in opened position.

Fig. 6 is a plan view illustrating the coupling of two couplers which are angled laterally with respect to each other in a direction opposite to that shown in Fig. 5, the same knuckle being in opened position.

2

Fig. 7 is a plan view showing the couplers of Fig. 6 moved closer toward coupled position.

Fig. 8 is a horizontal sectional view of a modification, the couplers being shown in buffed position.

Fig. 9 is a vertical sectional view taken along line 9—9 of Fig. 8.

Referring to the embodiment shown in Figs. 1 to 7 each coupler 10 is of the conventional type having a pivoted knuckle 11 and a guard arm 12. It will be observed that while a certain amount of slack exists between the contours of the coupled couplers, it is to be understood that my invention may be embodied in couplers having a greater or lesser amount of slack, or no slack, and therefore its application is not limited to the particular coupler illustrated. On the knuckle side of the coupler there is formed a pair of vertically spaced gathering wings 15 preferably having vertically disposed convexly curved cylindrical end surfaces 16. These wings are spaced laterally outwardly of the knuckle and project forwardly from the coupler body. Between wings 15 the coupler is recessed as at 17 to receive the forward end of guard arm 12 of the mating coupler. On the guard arm side of the coupler is provided a pair of wings in the form of sockets 18 having concavely curved cylindrical surfaces 19 complementary to surfaces 16 and adapted for engagement therewith during the coupling operation. If desired surface 16 may be formed spherical in shape and surface 19 correspondingly curved without departing from the spirit of the invention. Wings 15 and sockets 18 are so constructed and arranged that as two couplers which are in horizontally angled relationship, but within their gathering range, approach each other in the manner shown in Fig. 5, one of wings 15 will engage its complementary socket 18. Thus surface engagement between the wing and socket will always occur so long as the couplers are within their gathering range. After engagement between the wing and socket has taken place along surfaces 16 and 19 a rotating contact occurs therebetween as the couplers are being straightened. Rotation of the wing in the socket continues until the couplers are coupled. In neutral coupled position a clearance exists between curved surfaces 16 of the wings and the complementary surfaces of the sockets 18 as well as between the front face 20 of the coupler head and buffing face 21 of the knuckle. In pulled position of the couplers (Fig. 1) engagement takes place along pulling faces 22 of the knuckles, while in buffed position (Fig. 2), engagement occurs

between buffing faces 21 of the knuckles and front faces 20 of the coupler head. It will be observed that a clearance exists between the wings and their respective sockets in both buffed and pulled positions, the function of these parts being primarily to align the couplers and facilitate the coupling operation. However, engagement occurs between one of the wings and its socket when the couplers angle horizontally as shown in Fig. 3. This engagement in conjunction with the engagement between the knuckles serves to restrict angular movement between the couplers and thereby prevent the possibility of jack-knifing thereof in service.

It will be observed that inner surface 26 of wing 15 tapers rearwardly and inwardly from surface 16 so as to be in angled relationship to the centerline of the coupler. Surface 27 on socket 18 is parallel to surface 26 and spaced therefrom. These surfaces are so positioned that in service in the event of an outward distortion of guard arm 12 the cooperation of the wing and socket will be less apt to be affected than if these surfaces were positioned parallel to the coupler centerline and spaced apart the same amount. Thus for any given outward distortion of the guard arm in which it pivots about some point X, for example, at the juncture of the guard arm with the coupler head, any given point on surface 27 will move along a longer arc before engaging surface 26 on the wing than if these surfaces were formed parallel to the centerline of the coupler.

A feature of the gathering wings resides in the increased horizontal gathering range of the couplers to which they are applied. This is particularly illustrated in Fig. 5 where A and B designate the pivots of the two couplers. The position shown represents the maximum amount the couplers may be angled horizontally and still gather and couple. It will be observed that in order that the couplers may gather the engagement between wing 15 and socket 18 must occur on the side of the centerline joining pivots A and B opposite to that on which the couplers are angled. Thus the engagement as at 24 in Fig. 5 lies slightly below the centerline and, therefore, a turning moment about pivots A and B in the direction of arrow R will be exerted to align the couplers as they move together.

In the United States patent to A. J. Bazeley, No. 2,178,062, dated October 31, 1939, the aligning wings comprise wedge projections on the guard arms which engage wedge sockets on the knuckle side of the coupler, and, as two couplers approach, a sliding contact occurs between the inner surfaces of the projections and the side walls of the wedge sockets. However, with my invention the guard arm does not contact the side wall of the coupler head during the gathering operation and the initial contact between the approaching couplers takes place farther from the centerline of the couplers than in the Bazeley patent, thereby increasing the gathering range. It will be noticed in Fig. 5 that a substantial clearance as at 25 exists between the guard arm 12 and the side of the opposing coupler so that if my gathering wings were not applied to the couplers, the couplers would not gather until they were angled a lesser amount than shown i. e., to a position in which engagement between guard arm 12 and the side of the opposing coupler took place at a point slightly below the centerline through pivots A and B. It will be seen that the engagement between wing 15 and socket 18 occurs

5 curs laterally outwardly of the inner surface of guard arm 12 and inwardly of the end of the arm. Preferably it occurs in a plane transversely to the axis of the coupler which passes through the pivot pin for the knuckle. Thus my invention contributes materially toward increasing the gathering range of the couplers. In fact, it has been found that a coupler in accordance with the present invention may be readily made about 10% narrower than a coupler of the Bazeley type and yet have about a 10% greater gathering angle.

15 In Fig. 6 the couplers are shown angled to the opposite side of the centerline drawn through pivots A and B, the same coupler as in Fig. 5 having its knuckle opened. In this position the wings do not initially assist in aligning the couplers, the engagement occurring between the guard arm and the opened knuckle, the latter being at this time prevented from turning on its pivot by engagement with the other knuckle. The position shown illustrates the maximum angled position in which the couplers will gather. However, as the couplers straighten and move 20 toward fully coupled position the wing 15 on the coupler whose knuckle was open comes into engagement with socket 18 of the opposing coupler as illustrated in Fig. 7, thereby providing a turning moment about the pivots A and B. Thereafter the rotational contact between the wing and socket facilitates rolling of the knuckles into coupled position.

25 Gathering of the couplers when in vertically angled position is effected by the engagement of either of sloping surfaces 28 of the guard arm with upper or lower wing 15 depending on the 30 relative positions of the couplers as they move together.

35 Upper wing 15 (Fig. 4) has a horizontal surface 30 on its underside while lower wing 15 has a horizontal surface 31 on its topside. These surfaces cooperate with horizontal surfaces 32 on sockets 18 to limit relative vertical movement between mated couplers.

40 In the modification shown in Figs. 8 and 9 a single gathering wing 35 having a convexly curved end surface 36 is formed on the knuckle side of the coupler. This wing comprises vertical end wall 37 on which is located the curved surface 36, rearwardly diverging walls 38, and top and bottom walls 39 and 40 respectively. The 45 sockets 45 in the guard arm conforms in shape to wing 35 and has concavely curved surface 46 adapted for engagement with surface 36. When the couplers are in horizontally angled position, the action of the wings and sockets in aligning the couplers and facilitating the coupling operation is similar to that of the previous embodiment. With this form of the invention gathering 50 of the couplers when in vertically angled position is accomplished by the engagement of one of sloping walls 38 on wing 35 with the forward end of the socket as the couplers move together. In Figs. 8 and 9 the couplers are shown in buffed 55 position and it will be noted that a clearance exists between surfaces 36 and 46, thus avoiding any buffing stresses on the wings and sockets. Horizontal top and bottom walls 41 and 48, respectively, of socket 45 cooperate with walls 39 and 40 to limit relative vertical displacement of the mated couplers.

60 Thus my improved gathering wings and sockets increase materially the horizontal gathering range of the couplers and also facilitate the movement of the couplers to coupled position.

The curved engaging surfaces on the wings and sockets assure a rotational contact therebetween as the couplers are being aligned during coupling operations. In addition the couplers are restrained by the wings and sockets against vertical displacement relative to each other. Also, in the modification of the invention the wings and sockets provide for both horizontal and vertical gathering of the couplers.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. In a car coupler having a head, a forwardly facing projection on one side of said head having a rounded vertically extending end surface, and socket means on the other side of said head having a vertically extending curved rear wall complementary to said end surface on said projection, said projection being adapted to engage a curved rear wall of corresponding socket means of a similar mating coupler to align the couplers when the couplers approach for coupling while within coupling range, said rear wall of said socket being so positioned in a longitudinal direction as to be in spaced opposed relationship to the end surface of the projection of the mating coupler when the couplers are in coupled position.

2. Car coupler aligning means comprising a vertically positioned abutment surface on one side of the coupler head, said surface being convexly curved about a vertical axis, and a concave abutment surface on the other side of the coupler head, said convexly curved abutment surface being adapted to rotatively engage a corresponding concavely curved abutment surface of a mating coupler to rotate the couplers into alignment during coupling operations, said rear wall of said socket being so positioned in a longitudinal direction as to be in spaced opposed relationship to the convexly curved abutment surface of the mating coupler when the couplers are in coupled position.

3. In a car coupler having a knuckle and a guard arm, coupler aligning means comprising a wing on the knuckle side of the coupler head, said wing being spaced laterally outwardly of said knuckle and having a rounded end surface, and a socket on said guard arm having a continuous end surface complementary to said rounded end surface and adapted for rotational engagement with a corresponding rounded end surface on a wing of a mating coupler during initial contact between said surfaces when the couplers approach for coupling while within coupling range, said rotational engagement continuing until the couplers have been aligned and coupled.

4. A car coupler provided with lateral means for cooperation with similar means on another coupler to align the couplers during coupling operations, said means comprising a wing on one side of the coupler head and spaced laterally outwardly therefrom, said wing having a convexly curved end surface, and a socket on the other side of the coupler head having a concavely curved end wall curved complementally with said end surface of said wing and being adapted for full surface rotational engagement

with a corresponding convexly curved surface on the wing of a mating coupler when the couplers approach for coupling while within coupling range.

5. In a car coupler having a knuckle and a guard arm, gathering means for cooperation with similar means on a mating coupler to align the couplers during coupling operations, said means comprising a wing on the knuckle side of the coupler head having a forwardly facing end surface, said surface being cylindrically curved about a vertical axis, and a socket on said guard arm having a surface curved complementally to said curved end surface of said wing and adapted for rotational engagement with a corresponding cylindrical surface on a mating coupler for effecting alignment of the couplers as they approach for coupling while within coupling range.

6. Car coupler aligning means comprising vertically spaced projections on one side of the coupler head having forwardly rounded end portions, and vertically spaced sockets on the other side of the coupler head, each socket having a rear wall curved complementally with said rounded end portions of said projections, said rear wall being adapted for rotational contact with the corresponding rounded end portion of a projection on a mating coupler to align the couplers during coupling operations.

7. In a car coupler having a knuckle and a guard arm, coupler aligning means comprising a pair of vertically spaced wings on the knuckle side of the coupler head having rounded end portions, and a pair of complementary sockets on the top and bottom sides of said guard arm for receiving the corresponding wings on a mating coupler and adapted for rotational contact therewith to align the couplers during coupling operations.

8. In a car coupler having a knuckle and a guard arm, a pair of vertically spaced wings on the knuckle side of the coupler head, the coupler head being recessed between said wings for receiving the guard arm of a mating coupler, a pair of sockets on said guard arm for receiving the corresponding wings of a mating coupler for rotational engagement therewith to align said couplers during coupling operations, said wings and sockets having complementally curved contacting surfaces.

9. In a car coupler having a knuckle and a guard arm, coupler aligning means comprising a wing on the knuckle side of the coupler head having a rounded end surface, said wing being disposed intermediate the top and bottom of the coupler head, and a socket in the forward end of said guard arm for receiving the corresponding wing of a mating coupler, said socket having a rear surface curved complementally to said rounded end surface on said wing adapted to be engaged by a rounded end surface on a corresponding wing of a mating coupler to rotate the couplers into alignment as the couplers approach for coupling while within coupling range.

10. In a car coupler having a knuckle and a guard arm, coupler aligning means comprising a projection on the knuckle side of the coupler having a convexly curved forwardly facing end surface and a pair of diverging surfaces extending rearwardly from said end surface, and a socket in the forward end of said guard arm having a rear surface curved complementally with said end surface on said projection, said end surface on said projection being adapted for rotational engagement with the corresponding rear

surface of a socket of a mating coupler to align the couplers during coupling operations, said engagement between said surfaces continuing until the couplers have been coupled.

11. In a car coupler having a knuckle and a guard arm, coupler aligning means comprising a wing on the knuckle side of the coupler head, said wing being disposed intermediate the top and bottom of the coupler head, the forward end of said guard arm having a recess for receiving said wing, said recess having a surface arranged for engagement with the end of a corresponding wing of a similar mating coupler during alignment of the couplers, said surface on the guard arm and the end surface of said wing being curved complementally, one being convex and the other concave said engagement between said complementary surfaces continuing until the couplers have been coupled.

12. In a car coupler having a knuckle and a guard arm, coupler aligning means comprising a wing on the knuckle side of the coupler head having a convexly curved end surface and rearwardly extending diverging surfaces, said guard arm having a socket in the forward end thereof for receiving said wing of a mating coupler, said diverging surfaces being adapted to slidably engage the forward end of said socket of the mating coupler to align the couplers vertically during coupling operations, and said curved surface being adapted to engage a complementary surface

in said socket of the mating coupler to align the couplers horizontally after the couplers have been aligned vertically.

13. A car coupler having head, a knuckle pivoted thereto and a guard arm on said head, and coupler aligning means comprising a forwardly facing projection on one side of the coupler head and an abutment on the other side of the coupler head having a surface for engagement with a corresponding projection of a mating coupler to align the couplers as the couplers approach for coupling while in coupling range, said forwardly facing portion of said projection being spaced laterally outwardly from the side of the coupler head whereby contact between the coupler heads during alignment is confined to said projection and abutment, and sliding contact between said heads is avoided.
